UNITED STATES PATENT OFFICE

FRANKLIN E. ARNDT, OF GALION, OHIO, ASSIGNOR TO THE GALION IRON WORKS & MANUFACTURING COMPANY, OF GALION, OHIO, A CORPORATION OF OHIO

ROAD GRADER AND SCARIFIER

Application filed November 15, 1928. Serial No. 319,632.

This invention relates to road working machines and particularly to road graders provided or combined with scarifiers.

One of the objects of the present invention is to provide a combined road grader and scarifier in which the scarifier is carried by and supported from the draw bars which carry the scraping blade so that the whole weight of the draw bars, the circle and the yoke supporting the scraping blade may be utilized in forcing the scarifying teeth into the roadway.

A further object is to provide a structure of this character so constructed that the scarifier can be raised or lowered independently of the blade of the scraper and in this connection to so construct the machine that the scarifying may be done without scraping, scraping may be accomplished without scarifying or both scarifying and scraping may be accomplished at the same time.

Still another object is to so mount the scarifier upon the draw bars of the blade that by operating the means for tilting the draw bars and the blade transversely that the scarifier may be tilted so that the scarifier can be forced to cut deeper on one side than the other by raising the blade supporting means at the right hand or at the left as desired.

Other objects have to do with the details of construction of the scarifier and the means whereby the scarifier is raised or lowered and otherwise manipulated.

My invention is illustrated in the accompanying drawings, wherein:—

Figure 1 is a side elevation of a combined scarifier and grader constructed in accordance with my invention;

Figure 2 is a fragmentary longitudinal sectional view thereof;

Figure 3 is an elevation of the operating means for the scarifier;

Figure 4 is an elevation of a portion of the main frame showing the scarifier shaft supporting bracket in elevation;

Figure 5 is a top plan view of the scarifier, the pivot pin for the same being in section;

Figure 6 is an enlarged sectional view

through the bearing for oscillatably supporting the scarifier;

Figure 7 is a section on the line 7—7 of Figure 6.

Figure 8 is a fragmentary top plan view of the middle portion of my grader.

In these drawings, I have illustrated a grader of more or less well-known construction which includes the longitudinally extending frame beams 10, these beams being longitudinally arched so as to extend downward and forward at their front ends.

The forward ends of these beams are operatively supported upon the forward axle of a truck in a manner not necessary to describe and connected to draft mechanism not necessary to specifically refer to. The rear ends of these beams 10 are mounted upon a rear truck or axle in any ordinary manner. Inasmuch as these details will form no part of the present invention, it is not deemed necessary to more than refer to them.

Loosely connected to the forward truck, as for instance to the transverse beams 11 thereof, are the two divergent rearwardly extending draw bars 12. The forward ends of the draw bars are more or less flexibly connected to the beams 11 by means of a clevis 13, the clevis being connected to an eye bolt 14 so that the clevis may swing vertically upon the eye bolt or swing horizontally upon the eye bolt. The draw bars 12 connect to this clevis in a manner permitting the oscillation of the draw bars around the longitudinal axis of the clevis. This is no part of my present invention as it is a common construction in graders of the character stated.

Mounted for rotation upon the draw bars 12 is a yoke beam 15 semi-circular at its forward end, the two arms of the yoke extending rearward and downward and carrying the scraper blade 16, the scraper blade being pivoted to the arms as at 17. The semi-circular portion of the member 15 is supported upon the draw bars 12 for oscillation in a horizontal plane, or in the plane of the draw bars by means of a pivot bolt 18 passing through a transverse channel iron 19 connecting the draw bars and passing through

a transverse channel iron 20 which extends between the arms of the yoke 15, as shown in Figure 2.

The yoke 15 is apertured at a plurality of 5 points and a retractible bolt 21 coacting with said apertures is operatively supported upon the draw bars so that the yoke may be held in any rotatably adjusted position. This bolt 21 is operatively connected to the lever 22, in 10 turn connected to a pull rod 23 whereby the bolt may be retracted, the bolt being preferably projected by means of a spring not shown. This also forms no part of my present invention. It will be seen that with this 15 construction, the yoke which supports the scraping blade may be rotated around the axis of the bolt 18 to any desired position to thus angle the scraper blade with relation to the line of draft. The oscillative adjustment 20 of the yoke and scraper blade is secured in the instance disclosed by means of an arcuate rack 24 operatively mounted upon the yoke and engaged by a pinion 25, the shaft of which carries the beveled gear 26 having 25 meshing engagement with a beveled gear wheel mounted upon a shaft section 27. This shaft section extends rearward and is flexibly engaged with a shaft section 28 which extends to the operator's platform where it carries 30 an operating wheel. By this means the yoke 15 with the scraper blade may be rotated into any desired angular relation to the line of draft and the scraper blade then locked in 35 position by means of the bolt 21 engaging the semi-circular portion of the yoke 15.

For the purpose of raising or lowering the draft beams 12, I have illustrated vertical links 29. These are operatively connected at their lower ends to a transverse beam 30 40 mounted upon the draw bars and at their upper ends the links 29 have engagement each with a crank arm 31 carried by the shaft 32 extending rearward to the operator's platform and there operatively connected to 45 operating means whereby one or the other of the shafts may be rotated.

If both of the shafts are rotated in the same direction, it is obvious that the draw beams will be raised or lowered. If one of 50 the operating means be turned in one direction and the other in another, it is obvious that one side of the scraping blade will be lowered and the other side of the scraping blade raised, or in other words that the draw 55 bars will be tilted, thus tilting the yoke 15 and the scraper blade. Any suitable means may be used for accomplishing this result, the mechanism which I have illustrated being merely one of the conventional means for this 60 purpose.

My present invention contemplates mounting a scarifier element for vertical movement in front of the scraping blade and entirely supported by the draw bars, this mounting 65 being such that to a certain extent, the adjust-

ment of the scarifier shall be independent of the adjustment of the blade and the scarifier may be operated independently of the blade. To this end I mount upon the draft beams 12, the brackets 33 which brackets support the transverse shaft 34 upon which are mounted the segment gears 35. There are two of these segment gears 35 disposed on each side of the yoke 15. Mounted in the upper portion of the bracket 33 is the transverse shaft 36 which carries upon its ends the pinions 37 engaging with the segment gears 35. The shaft 36 carries upon it a worm wheel 38 and engaging this worm wheel is the worm 39, the shaft of which has flexible engagement with a shaft section 40 extending rearward and flexibly engaged with the shaft section 41 which extends upward and rearward and is flexibly coupled to a shaft section 42 carrying thereon the bevel gear 43.

This bevel gear is engaged by a beveled gear wheel 44 on a manually operable shaft 45 carrying the operating lever 46 at its upper end. By rotating the shaft 45 in one direction or the other, it is obvious that the shaft 46 will be rotated in one direction or the other and thus cause the upward movement of the segment gears 35 or the downward movement thereof. These segment gears have outwardly projecting wrist pins 47 engaged with the depending links 48.

The scarifying element 49 is formed with outwardly projecting pairs of lugs 50 between which the links 48 are disposed and to which the links are pivotally connected by means 100 of the pivot pins 51. This scarifying element or frame consists of a transversely extending casting formed to provide a plurality of downwardly and forwardly slanting open ended sockets 52 within which the scarifying teeth 53 are disposed. These teeth are preferably pointed at opposite ends and the rear edge of each tooth is formed with a plurality of notches 54 through which passes a locking pin 55 which intersects the socket and intersects one or another of these notches. Thus the scarifying tooth may be held in a plurality of different adjusted positions so that as it wears off the tooth may be lowered and when entirely worn on one end the tooth may be turned over and the other end used until worn out.

The rear of the scarifying element 49 is provided with two pairs of upwardly and rearwardly projecting ears 56 which are relatively long, each pair of ears being spaced from each other to receive between them a scarifying push bar 57. There are two of these push bars. These push bars are convergently arranged and at the rear end are apertured for the passage of a pin 58. These bars constitute thrust elements holding the scarifier in predetermined position against the thrust exerted by the ground or roadway.

This pin extends through a circle connec- 125

tion comprising a collar or sleeve 59 through which the bolt 18 passes, this collar being formed with a transversely extending horizontally disposed sleeve 60 through which the pin 58 passes. Thus it will be seen that the push bars 57 for the scarifier oscillate about the same axis as does the blade supporting the yoke while at the same time the push bars 57 may be vertically adjusted independently of any vertical adjustment of the yoke.

It will be seen that with the construction which I have heretofore described, the whole weight of the main draw bars 12 and the weight of the scraper and the scraper supporting yoke bears downward upon the scarifier. This secures rigidity when at work as the stresses are all carried up through the blade unit first and then to the frame of the machine and this eliminates practically all vibration and chattering. The scarifier when raised is disposed up under the circle, thus forming a very compact unit when operating the blade independently of the scarifier. The machine can be operated to do scarifier work and blade work at the same time or operated to do scarifier work independent of blade work or to do blade work independent of the scarifier, thus forming a combination unit which is controlled while it will work by the lifting mechanism mounted upon the draft beams.

If it is desired to do scarifying without scraping, the segment gears 33 are turned to allow the scarifier to be lowered approximately to its limit, the blade being raised. The teeth of the scarifier at this time will be in approximate contact with the ground.

The blade control hand wheels which control the raising and lowering of the draw bars 12 are operated to allow the draw bars and blade to move downward which will force the scarifier into the ground but the draw bars are only let down sufficiently so that the blade will clear the scarified work. If the scarifying be deep the blade at some times will touch some of the loose material but this will not in any way interfere with the proper operation of the scarifier.

Inasmuch as means are provided whereby the draw bars may be transversely tilted so as to permit one side of the blade to cut deeper than the other, it is possible to so adjust the draw bars and thus the scarifier can be forced in deeper on one side than the other as for instance by raising one of the draw bars and lowering the other draw bar, thus tilting in effect the frame upon which the scarifier is mounted. This, of course, is due to the fact that the scarifier is entirely mounted on and tilts with the draw bars. If it is desired to do scarifying work and scraping at the same time, the draw bars are lowered to depress the blade the required amount and at the same time the scarifier may be slightly raised so as to permit the blade to

get down into the loosened material. Of course if it be desired to do scraping without scarifying, the scarifier is raised to its maximum height where it is carried along under the blade circle. By this principle, I have provided an independently operated scarifier, which may be raised or lowered to suit conditions.

I claim:—

1. A grading machine having a main frame, draw bars operatively connected to the main frame for vertical movement, a scraper supporting yoke mounted upon the draw bars for oscillation in a horizontal plane and carrying a scraper, a scarifier disposed in front of the scraper, a shaft mounted upon the draw bars, segment gears on the shaft, a worm wheel on the shaft, a manually operable worm for rotating the shaft and engaging the worm wheel, links pivotally connecting the scarifier to said segment gears, and scarifier push bars pivotally engaged with the scarifier and extending upward and operatively pivoted at a point adjacent the rotational axis of the yoke to the draw bars.

2. A grading machine having a main frame, draw bars connected thereto at their forward ends for vertical movement, manually operable means for raising or lowering the draw bars independently of each other, a scraper supporting yoke mounted upon the draw bars for movement therewith and for oscillation around a vertical axis, a scraper carried by the yoke, a scarifier disposed in front of the scraper, a shaft mounted on the draw bars and segment gears carried thereby and pivotally connected to the scarifier, a second shaft mounted upon the draw bars and having gear wheels engaging the segment gears, manually operable means for rotating the second shaft, and push bars pivoted to the scarifier extending upward and rearward therefrom, the rear ends of the scarifier push bars being operatively pivoted to the main draw bars at a point adjacent the center of rotation of said yoke.

3. In a grading machine, the combination with a main frame, of draw bars connected to said main frame, a scraper mounted on said draw bars and operatively connected thereto for horizontal pivotal movement relative thereto, a scarifier carried by said draw bars in advance of the scraper, and thrust resisting members extending between the scarifier and the pivotal connection of said scraper to the draw bars.

4. In a grading machine, the combination with a main frame, of draw bars operatively mounted on said frame for vertical and tilting movement, a scraper operatively carried by said draw bars for movement therewith, and pivotally mounted for independent horizontal angular movement, a scarifier operatively carried by said draw bars and disposed in advance of the scraper, and means con-

necting said scarifier with said scraper pivot.

5. In a grading machine, the combination with a main frame, of draw bars mounted on said main frame for vertical and tilting movement, a yoke mounted upon said draw bars for rotational movement in a plane transverse to the draw bars, a scraper pivotally mounted on said yoke for movement therewith, a scarifier disposed in advance of the scraper, push bars connecting said scarifier with the pivotal center of the yoke, and means mounted upon the draw bars whereby the scarifier may be raised or lowered independently of the vertical movement of the draw bars.

6. In a grading machine having a main frame, draw bars operatively connected to the main frame for free lateral movement and for vertical movement, means for independently raising or lowering either of said draw bars, a scraper supporting yoke mounted upon the draw bars for oscillation in an approximately horizontal plane and carrying a scraper, a scarifier disposed in front of the scraper, a shaft mounted upon the draw bars, segment gears mounted on the shaft, manually operable means for rotating said shaft, links pivotally connecting the scarifier

directly to the segment gears, and means connected to the scarifier and pivotally engaged with the draw bars and resisting thrust against the scarifier, the scraper being thus mounted for independent rotation relative to the scarifier.

7. In a grading machine, a main frame, draw bars mounted upon said main frame for lateral swinging movement and for vertical adjustment, means on the main frame whereby the draw bars may be transversely tilted, a scarifier disposed below the draw bars, a shaft mounted directly on said draw bars, segment gears on said shaft, each having a linked connection to the scarifier, manually operable means for oscillating said segment gears to thereby raise or lower the scarifier relative to the draw bars, push bars operatively connected to the scarifier and pivotally connected to the draw bars, and a scraper carried by the draw bars rearward of the scarifier, the scraper being mounted for rotational adjustment in an approximately horizontal plane independently of the scarifier.

In testimony whereof I affix my signature.

FRANKLIN E. ARNDT.
